[57] CLAIM

The ornamental design for an antenna attachment assembly, as shown.

DESCRIPTION

FIG. 1 is a perspective view of an antenna attachment assembly showing our new design;

FIG. 2 is a top elevational view thereof;

FIG. 3 is a bottom elevational view thereof;

FIG. 4 is a front elevational view thereof;

FIG. 5 is a left side elevational view thereof;

FIG. 6 is a back elevational view thereof; and,

FIG. 7 is another perspective view thereof.

The broken line showing of the telephone in FIG. 7 is for illustrative purposes only and forms no part of the claimed design.
